UNITED STATES PATENT OFFICE.

JOHN B. WOOD, OF POULTNEY, VERMONT.

IMPROVEMENT IN ELASTIC PADS FOR HORSESHOES.

Specification forming part of Letters Patent No. 159,292, dated February 2, 1875; application filed April 6, 1872

To all whom it may concern:

Be it known that I, JOHN B. WOOD, of Poultney, in the county of Rutland and State of Vermont, have invented certain Improvements in Horseshoe-Packings, to prevent snow from balling in horses' feet, of which the following is a specification:

Figure 1 is a plan of the under side of a horseshoe, showing retaining-points near the heel and a flange near the toe, for keeping the packing in place. Fig. 2 is the packing shown in perspective, the side next the foot being uppermost. Fig. 3 is the same, the side next the ground being uppermost.

A is the groove in the packing, to admit the frog of the foot. B is the flange, forged on the inner edge of the toe of the shoe, under which the toe of the packing is forced to pro-

tect it from the backward pressure of the snow. C is the retaining-point, forged from the shoe to fit in the notch of the packing. D is the shoulder to the retaining-point, to prevent the packing moving backward. E is the notch in the rubber, for the retaining-point.

I make no claim to the invention of a rubber packing for horseshoes, for I am aware that it is not new; but

I claim—

A horseshoe provided with the flanges B C, in combination with the elastic pad provided with the concavity A, for the purpose set forth.

JOHN B. WOOD.
